UNITED STATES PATENT OFFICE.

FRED W. COREY, OF TILTON, NEW HAMPSHIRE.

KNITTING-MACHINE NEEDLE AND METHOD OF MAKING SAME.

1,425,239.

Specification of Letters Patent. Patented Aug. 8, 1922.

Application filed November 6, 1920. Serial No. 422,175.

To all whom it may concern:

Be it known that I, FRED W. COREY, a citizen of the United States, residing at Tilton, county of Belknap, State of New Hampshire, have invented a certain new and useful Improvement in Knitting-Machine Needles and Methods of Making Same, of which the following is a specification, reference being had therein to the accompanying drawings.

10 The invention relates to an improvement in knitting machine needles and process of making same.

In the manufacture of latch needles for use in knitting machines heretofore when made by machinery, several distinct operations are required. One object of the present invention is to reduce the number of operations required to prepare the body of the needle ready for the formation of the slot to receive the latch. Another object of the invention is to reduce the size of the forward portion of the blank from a point somewhat back of the cheek portion to the end of the hook portion by a compression so as to densify and strengthen that portion of the needle rather than by either cutting down the blank or by drawing it out, or by swaging in the ordinary way, in which the surplus stock is entirely pressed out to one side instead of being compressed to a more dense formation as by my invention. Another object of the invention is to obtain an absolute uniformity in the size and shape of the needle by performing all of the swaging operation at one time rather than by different operations.

In the usual manufacture of latch needles, the blank consists of a round wire which is put through several separate distinct operations to reduce the size of the wire at the forward portion of the blank within which the cheeks and the hook are later to be formed, to swage the cheek portions, to form the cheeks, to taper the tip portion, to turn the forward end to form the hook, to form the pivot holes in the cheeks, and to make the slot between the cheeks. All these separate operations are performed before the needle is ready to receive the latch.

50 By my method of forming the body of the needle ready for the latch, I start with a flat blank of uniform thickness and by a single operation swage the forward part of the blank to reduce the thickness of that portion to the size desired for the hook, and point and form the hook and the point, and

prick tapered holes in the cheek portion. I accomplish the above by means of a pair of dies of special form. If the needle is to be a latch needle, the formation of the slot 60 and the attachment of the latch are accomplished by subsequent separate operations.

The invention will be fully understood from the following description when taken in connection with the accompanying drawings, and the novel features thereof will be pointed out and clearly defined in the claim at the close of this specification.

The drawings are all on an exaggerated scale to more clearly illustrate the invention. 70

In the drawings, Fig. 1 is a plan view of a latch needle of the character produced by my invention.

Fig. 2 is an edge view of the body of the needle shown in Figure 1. 75

Fig. 3 is a plan view of the blank from which the body of the needle is formed.

Fig. 4 is an edge view of the blank.

Fig. 5 is a cross section of a pair of dies embodying the invention. 80

Fig. 6 is a plan view of one of the dies shown in Fig. 5.

Fig. 7 is a section on line 7—7 of Fig. 6.

Fig. 8 is a section on line 8—8 of Fig. 6.

Fig. 9 is a plan view of the body of the 85 needle as it is made by the dies before the slot for the cheeks is formed.

Fig. 10 is an edge view of the needle body shown in Fig. 9.

Fig. 11 is a section on line 11—11 of Fig. 9. 90

Fig. 12 is a plan view of a form of needle in which the back of the reduced forward portion of the needle is set back on a line with the main body portion.

Referring now to the drawings, the finished needle as shown in Figures 1 and 2 comprises a blade or body portion 1, a cheek portion having a slot 3, whereby the two cheeks 2—2 are formed, a hook portion 4 bent at its forward end and terminating in 100 a reversely turned portion 5, and a latch 6 pivoted by a pin 7 between the two cheek members 2—2. From a point *b* somewhat back of the hook portion to the point *c* where the tip of the hook begins to taper, 105 the needle is usually of uniformly less diameter than the butt end of the needle, from the point *b* back to the rear end.

A part of my invention consists of providing a pair of dies A—B, between which 110 the entire needle portion, with the exception of the slot for the latch, is formed, and by

which at a single swaging operation the needle is shaped, the forward part is reduced in diameter, the point is formed and holes are punched to form countersinks for the 5 pivot hole which is later to be drilled out for the latch pivot. The two dies are exact counterparts of each other, except that one is right and the other is left.

Each die plate 8 as shown in Figures 5, 6, 10 7 and 8, has a depression 9 sunk therein to exactly half of the thickness of the needle which is to be formed and of the contour of the needle in plan view.

The hook portion of the needle from *b* 15 to *c* is of slightly less diameter than the thickness of the body portion 1, as shown in Figure 2, and the outer end 5 of the hook portion from the point *c* to the end is tapered to form a point. In order to form 20 the hook portion 4 of lesser diameter, as already described, with its tapered outer end 5, the die recess 9 is made of corresponding shape, being of less depth from the point *b'* to the outer end of the tip than the part 25 which forms the body portion from the butt end to *b'*, as shown in Figure 7. If the hook from *b'* to *c'* is to be of uniformly less diameter than the body of the needle, then the recess in the die from *b'* to *c'* will be also of uniformly less depth than the depth of the rear portion of the recess, and the recess from the point *c'* to the tip end will have converging walls both at the bottom and sides 30 10, as shown in Figure 6.

In order to form in each side of the cheek portions of the needle counter-sunk holes 15 35 for the location of the pivot holes and for the heading over of the pivot pin 7 of the latch, there is formed in each die a conical pointed projection 11. Preferably the die plate 8 is beveled off at the sides and ends, as shown at 12, so as to form sharp cutting edges 13 at the side edges of the depression 40 of the die.

The blank 14 from which the needle is 45 made is preferably shaped something as shown in Figure 3, the forward end portion *a* of the blank being made flaring so as to give sufficient width for the hook portion of 50 the needle, the rearward portion being of less width so as to avoid unnecessary waste of stock. The blank 14 is preferably of uniform thickness throughout as shown in Figure 4, being equal at least to the thickest 55 part of the needle to be formed, so that the forward portion of the blank out of which the hook is formed is thicker than the hook and pointed portion of the finished needle. The upper and lower die plates are mounted 60 in any suitable power press.

The blank is placed on the lower die plate B in a proper position over the die depression, and the upper die A is then forced down upon the lower die in any well-known 65 manner of operating a power press.

When the dies are brought together, the blank will be cut by the edges 13 thereof to the contour of the needle, as shown in plan view, and the portion which forms the hook end will be compressed in accordance 70 with the depression; that is, the hook portion of the dies being of less depth than the body portion and the blank being of uniform thickness throughout, the hook portion of the needle will not only be died out to the proper contour but will also be compressed. This compression will be greatest at the pointed end of the needle because the die 75 depressions are more shallow at that part. At the same time also the conical points 11 80 in the two dies will prick the conical depression 15 into the two cheek faces of the blank.

By the above method of forming the needle, there is performed at one operation the 85 shaping of the blank which has heretofore been performed by several operations, and the hook is formed without bending the wire but by dieing it out of the blank, and furthermore the metal is compressed at the hook 90 portion, thereby making it much denser and therefore much stronger and more durable.

For instance if the blade of the finished needle is to be 19/1000 thick in its thickest portion from the rear end to *b'*, and the forward portion in front of the cheeks is to be reduced to 15/1000 and still further reduced by tapering at the hook end, then I start with a blank 19/1000 thick throughout its 100 entire length. In that case the recess in each die at its deepest part is 9 1/2/1000 deep and in the forward part from *b* to *c* it is 7 1/2/1000, with a lesser depth at the point from *c* to the end, so that when the two dies are brought together the depth of the combined recesses is 19/1000 at its deepest portion and the portion which is of lesser depth is 15/1000 with still less depth at the point. Now when the blank is placed in position 105 and the dies are forced together, the portion of the needle which is to be 19/1000 thick will be died out to proper contour in width, while the portion which is to be of less thickness will not only be died out to the requisite contour in width but will also be compressed, 110 the compression being the greatest where the needle is the thinnest, namely at the pointed end.

After the needle body is thus far formed, 115 the slot 3 will be made by a separate operation, in well known manner, and the conical pivot holes 15 will be drilled out for the pivot for the latch, the flaring outer portions of the pivot holes allowing for the heading over of the pivot. By reason of the countersunk pivot holes being formed by the points 11 of the die, there is an assurance 120 that they will always be accurately located and always be uniform.

If the style of needle desired is to have 130

the back of the needle straight from the rear end to the beginning of the turn of the hook, as shown in Figure 12, instead of having the offset 16 as shown in Figure 9, the die 5 depression will also have a straight back wall 17 as shown in Figure 12, so that the straight edge will be formed at the same time the blank is died out. In the ordinary 10 method of constructing needles where the wire is drawn out and made of different diameters in different parts of its length, the needle is first made with the offset and then if it is desired to have a straight back the needle has to go through another operation 15 to straighten the back.

By my method of forming the needle there is not only obtained the advantage of compression of the metal in forming the

reduced portion of the needle and of lessening the number of separate operations, but 20 also there is ensured an exact uniformity in the product.

While I have described and illustrated the invention as applied to a latch needle, it is obvious that it is equally applicable to the 25 manufacture of others.

What I claim is:—

The method of forming a knitting needle consisting of dieing out the needle from a blank and at the same operation swaging 30 the pointed portion of the needle to make it more dense than the remainder of the needle.

In testimony whereof I affix my signature.

FRED W. COREY.
